DESCRIPTION

USPC D24/169, 186, 129, 223; D10/81, 96

FIG. 1 is a perspective view of a blood flow chamber showing
our new design;

CPC A61B 5/14535; A61B 5/14557; A61B

FIG. 2 is a top plan view of the blood flow chamber of FIG. 1;
FIG. 3 is a bottom plan view of the blood flow chamber of

5/1455; A61B 2562/185; A61B 5/1495;

FIG. 4 is a side elevation view of the blood flow chamber of
FIG. 1;

A61M 1/367; A61M 39/10; A61M 2205/3313;

FIG. 5 is one end elevation view of the blood flow chamber of
FIG. 1; and,

A61M 2230/205; A61M 2230/207; A61M

FIG. 6 is another end elevation view of the blood flow cham-
ber of FIG. 1.

2205/3306; Y10T 436/11

The broken lines in the drawings illustrate portions of the
blood flow chamber and form no part of the claimed design.
